DESIGN.

—o—
J. LYALL.

BAG.

D
No. 17,041.

Patented Dec. 28, 1886.

UNITED STATES PATENT OFFICE.

JAMES LYALL, OF NEW YORK, N. Y.

DESIGN FOR A BAG.

SPECIFICATION forming part of Design No. 17,041, dated December 28, 1886.

Application filed August 21, 1886; Serial No. 211,571. Term of patent 14 years.

To all whom it may concern:

Be it known that I, JAMES LYALL, of the city and State of New York, have invented a new Design for Coffee, Grain, and Seed Bags, 5 of which the following is a specification.

This design is shown in the accompanying photograph.

Coffee, grain, and seed bags are generally of uniform color and pattern throughout.

10 This design relates to the appearance and ornamentation of the bag, whereby the plain and disagreeable look of the bag is removed.

The ground of the bag is mottled in appearance, the same being composed of small rectangular figures contrasting in color, as shown 15 at *a*. The colored stripes *b* and *c* run length-

wise of the bag, said stripes being composed of small rectangular figures, so that the stripes have a mottled appearance as well as the ground.

20

I claim—

The design for a coffee, grain, and seed bag, consisting in the design of the longitudinal stripes and the mottled ground, composed of small rectangular figures contrasting in color, 25 substantially as described and represented.

Signed by me this 17th day of August, 1886.

JAMES LYALL.
